United States Patent Office

Des. 180,995
Patented Sept. 17, 1957

180,995

MULTIPLE DESK UNIT

Arthur W. Carlson, Muskegon, Mich., assignor to E. H. Sheldon & Co., Muskegon, Mich., a corporation of Michigan

Application January 11, 1957, Serial No. 44,475

Term of patent 14 years

(Cl. D33—7)

Fig. 1 is a perspective view of the multiple desk unit; and

Fig. 2 is a plan view thereof.

The multiple desk unit is symmetrical, so that a perspective view taken from a direction opposite to that of Fig. 1, would be substantially identical.

I claim:

The ornamental design for a multiple desk unit, substantially as shown and described.
